US00D905919S

(12) **United States Design Patent** (10) **Patent No.:** **US D905,919 S**
(45) **Date of Patent:** **** Dec. 22, 2020**

(54) **HAND VACUUM COMPONENT FOR A VACUUM CLEANER**

(71) Applicant: **SharkNinja Operating, LLC**, Needham, MA (US)

(72) Inventors: **Scott Niedzwecki**, East Walpole, MA (US); **Luis A. Canas**, Stoughton, MA (US); **Owen R. Johnson**, Needham, MA (US)

(73) Assignee: **SharkNinja Operating LLC**, Needham, MA (US)

(**) Term: **15 Years**

(21) Appl. No.: **29/658,920**

(22) Filed: **Aug. 3, 2018**

Related U.S. Application Data

(63) Continuation of application No. 29/603,071, filed on May 5, 2017, now Pat. No. Des. 870,406.

(57) **CLAIM**

The ornamental design for a hand vacuum component for a vacuum cleaner, as shown and described.

DESCRIPTION

FIG. 1 is a front view of a hand vacuum component for a vacuum cleaner, showing our new design;

FIG. 2 is a back view thereof;

FIG. 3 is a left side view thereof;

FIG. 4 is a right side view thereof;

FIG. 5 is an enlarged perspective view of the hand vacuum component for a vacuum cleaner detached from the rest of the vacuum cleaner;

FIG. 6 is a left side view thereof;

FIG. 7 is a right side view thereof;

FIG. 8 is a front view thereof;

FIG. 9 is a back view thereof;

FIG. 10 is a top view thereof; and,

FIG. 11 is a bottom view thereof.

The broken lines are included for the purpose of illustrating portions of the hand vacuum component for a vacuum cleaner that form no part of the claimed design.

1 Claim, 7 Drawing Sheets
